UNITED STATES PATENT OFFICE.

EDWIN V. BABBITT, OF FAIRHAVEN, MASSACHUSETTS.

TOY ACROBAT.

Application filed June 8, 1926, Serial No. 114,485.

This invention relates to a toy including a figure simulating an acrobat and operable to cause said figure to make motions resembling those of an acrobat engaged in turning hand springs.

In my application for a patent for a toy acrobat, filed July 31, 1925, Serial No. 47,272, I have disclosed a toy comprising a base, bearings rising from the base, inflexible upper shafts rotatably mounted in the bearings, flexible shafts connected to the upper ends of the upright shafts and rising thence and curving toward one another, and a body connected to the adjacent parts of the springs, said adjacent parts constituting a horizontal axis about which the body is revoluble by the rotation of the shafts. Said base is adapted to rest on a table, and the shafts are manipulated manually by the user.

The present invention is embodied in a toy in which the base is supported by running gear including traction wheels, adapted to run on a floor and fixed to an axle constituting an element of means rotating the shafts and revolving the figure when the toy is moved along the floor, the revolving movement of the figure being caused wholly by the rotation of the traction wheels.

Of the accompanying drawings forming a part of this specification,—

Figure 1 is a front view of a toy embodying the invention, parts being shown in section.

Figure 2 is a side view.

Figure 3 is a bottom view.

Figure 4 is a section on line 4—4 of Figure 2.

Figure 5 shows in perspective and separately a portion of the base or platform hereinafter described, and one of the upright shaft bearings, the bearing being partly completed.

Figure 6 shows the platform in section on line 6—6 of Figure 5, and the bearing in elevation, completed and engaged with the platform.

Figure 7 is a section on line 7—7 of Figure 6.

The same reference characters indicate the same parts in all of the figures.

The figure simulates an acrobat or clown and includes a body 12 and curved flexible shafts 13, fixed to the upper portion of the body and projecting from opposite sides thereof, the shafts 13 simulating the arms

of the figure and being preferably composed of helically coiled wire. The shafts are preferably fixed to the body by the insertion of their inner ends in sockets 14 in the body, the diameter of the sockets being less than that of the convolutions of the wire, so that the end convolutions are compressed and are caused by their effort to expand to firmly engage the socket walls.

15 designates a platform, preferably of sheet metal and provided with a marginal stiffening flange 16. Fixed to and rising from the platform are bearings for the inflexible upright shafts hereinafter described. 70 Each of said bearings is preferably composed of a single piece of sheet metal, formed as best shown by Figures 3, 6, and 7. The piece bears at its lower edge on the platform and includes a central portion 17, having an upper bearing ear 18, and a lower bearing ear 19, said ears having perforations 20, receiving the lower end portions of the upright shafts. The piece also includes brace portions 21, projecting obliquely from the central portion 17, and provided with tongues 22 (Figure 5) inserted in slots 23 in the platform and bent to bear on the under side of the latter. The tongues 22 and the lower bearing 19 are vertical, before the bearing is engaged with the platform, so that a downward movement of the sheet metal piece enters the tongues 22 in the slots 23, and enters the lower bearing ear in another slot 24, said tongues and ear being subsequently bent to bear on the under side of the platform, as shown by Figures 6 and 7. Although I have thus particularly described the preferred construction of the bearings, I am not limited thereto.

Journalized in the bearings are the lower end portions of inflexible upright shafts, preferably composed of central sections 25, which may be wooden rods, upper and lower socketed spherical sections 26 and 27, fixed to the ends of the sections 25, and lower sections 28, preferably wire rods, fixed in the lower sections 27 and inserted loosely in the orifices of the bearing ears 18 and 19, and projecting below the platform, as shown by Figure 1.

The outer ends of the flexible shafts 13 are fixed to the upper ends of the upright shafts, preferably by the insertion of the outer convolutions of the wire in sockets 29, in the upper sections 26, as shown by Figure 4, the convolutions being compressed

2 by the socket walls, the lower sections 27 constituting enlarged portions of the upright shaft which bear on the upper bearing ears 18, so that the weight of the shafts and of 5 the toy figure is supported by said ears.

The platform 15 is supported by running gear which includes an axle 31, journaled in bearings in the flange 16, and traction wheels 32, fixed to the axle, so that the axle is rotated by the rotation of the wheels, the axle being substantially at right angles with the upright shafts.

The axle is connected with the upright shafts by gearing adapted to transmit torque 15 from the axle through the upright and flexible shafts, and thereby revolve the body about a horizontal axis formed by the inner ends of the flexible shafts joined to the body, the shafts being rotated simultaneously in 20 opposite directions.

Said gearing includes larger gears 33, having hubs which are fixed to the lower ends of the reduced upright shaft sections 28, and smaller gears 34 which are fixed to the axle 31, and mesh with the larger gears. Said 25 gears are preferably formed as stampings from sheet metal, the preferred form thereof being clearly shown by Figures 1 and 3. They are in effect crown bevel gears, and 30 may have the usual conventional form of bevel or meter gears if desired. The smaller gears engage the larger gears at the outer marginal portions of the latter, so that the larger gears and the shafts driven thereby, 35 are rotated simultaneously in opposite directions.

When the described toy is moved on a floor, the figure is continuously revolved in a 40 vertical plane and simulates an acrobat engaged in turning hand springs. The running gear may include a rear idle traction wheel 36, journaled in bearings in a rearwardly projecting bracket 37, fixed to the platform flange. The preferred arrangement 45 is such that when the toy is running on a floor, the platform and the upright shafts are slightly inclined, as shown by Figure 2, and the center of gravity is between the forward traction wheels 32 and the rear traction wheel 36.

I claim:

1. A toy acrobat comprising a platform, upright shafts supported by and rising from said platform, wheels supporting the plat-

form, rotation transmitting means driven by 55 the wheels and arranged to rotate said shafts in respectively opposite directions, a figure body located between said shafts, and flexible arm members secured to and projecting from opposite sides of the body, each being 60 curved downwardly and secured to the adjacent upright shaft in continuation thereof; said arm members constituting at the same time means for supporting the body and means for rotating the body about a transverse axis passing through the points at which the arms spring from the body.

2. A figure toy as specified by claim 1, the platform being of sheet metal, the upright shafts having enlarged upper end portions 70 and reduced lower end portions, and the said bearings being composed of single upright sheet metal pieces, bearing at their lower edges on the platform and including central portions having bearing ears at their upper and lower ends, perforated to receive the reduced ends of the upright shaft portions and brace portions projecting obliquely from the body portions, and provided with tongues inserted in slots in the platform and bearing 75 on the under side thereof, the lower bearing ears being inserted in other slots in the platform and bearing on the under side thereof, the enlarged upper end portions of the upright shafts bearing on the upper bearing ears, so that the weight of the torque-transmitting shafts and the figure is supported by 80 said upper ears.

3. A figure toy as specified by claim 1, the lower ends of the upright shafts projecting 90 through the platform, the said gearing comprising larger bevel gears fixed to the shafts below the platform, and smaller bevel gears fixed to the axle and meshing with the larger gears, the arrangement being such that the 95 larger gears and shafts are rotated simultaneously in opposite directions.

4. A figure toy as specified by claim 1, the running gear including also a rear idle traction wheel and bearings therefor projecting 100 rearwardly from the platform, the arrangement being such that the center of gravity is between the traction wheels on the axle and the rear traction wheel.

In testimony whereof I have affixed my 105 signature.

EDWIN V. BABBITT.
